BICYCLE

Leroy H. Gutknecht, 202 Terrace Drive,
Hudson, Iowa 50643

Filed June 19, 1972, Ser. No. 264,200

Term of patent 14 years

Int. Cl. D12—11

U.S. Cl. D12—111

Fig. 2

Fig. 4

Fig. 1

Fig. 5

Fig. 3

FIG. 1 is a side elevational view of a bicycle showing my new design;

FIG. 2 is a top plan view thereof;

FIG. 3 is a side elevational view thereof opposite to that shown in FIG. 1;

FIG. 4 is a front elevational view thereof; and

FIG. 5 is a rear elevational view thereof.

I claim:

The ornamental design for a bicycle, substantially as shown.
